UNITED STATES PATENT OFFICE

THOMAS J. WATSON, OF SHORT HILLS, NEW JERSEY, ASSIGNOR TO THE TABULATING MACHINE COMPANY, OF ENDICOTT, NEW YORK, A CORPORATION OF NEW JERSEY

ACCOUNTING MACHINE WITH PUNCHING ATTACHMENT

Application filed April 4, 1925. Serial No. 20,586.

This invention relates to improvements in devices for perforating record cards such as are used in Hollerith tabulating machines, whereby the cards are punched concurrently with the operation of a cash register.

It is sometimes desirable that each transaction carried out on a cash register be recorded in permanent form, as on a tabulating card, so that the data may be sorted, tabulated, listed or classified by tabulating machines of known type and my present invention covers a device which automatically punches a record of the transaction on a card whenever the cash register is operated.

One object of my invention is to provide a device which will permit cash registers of known type to be used in connection with card punches of known type, the invention residing more particularly in the provision of supplementary devices to be connected with the cash register and adapted to control the operation of the punching devices.

Another feature of the invention is the provision of a cash register combined with a punching device in which controlled electric circuits are provided intermediate the cash register and the punching devices to the end that the amounts set up in the cash register may be electrically transferred to the punching devices.

Provision is made for transferring the amounts representative of dollars, dimes, cents, etc., to the punching attachment so that the dollars, dimes, cents, etc., may be punched in different columns upon the card and preferably at successive punching operations but during a single operation of the cash register.

Further and other advantages of the present invention will appear in the accompanying specifications and claims and in the drawings which by way of illustration show what I now consider to be a preferred embodiment of the invention.

In the drawings:

Fig. 1 illustrates a typical cash register with the 70 key depressed, and with outer portions cut away to show some of the contact segments.

Fig. 2 is a side elevation in section on line 2—2 of Fig. 1, showing contact segments.

Fig. 3 is a top plan view of a card punching machine of a well known type.

Fig. 4 is a sectional side elevation of the 55 punching machine, on line 4—4 of Fig. 3.

Fig. 5 is an enlarged detail plan of a portion of the punching machine, taken on line 5—5 of Fig. 4.

Fig. 6 is a detail of the cash register showing method of setting up the contacts.

Fig. 7 is a view on line 7—7 of Fig. 1 showing the revolution rack with some related details.

Fig. 8 shows the commutator and brushes. 65

Fig. 9 is a sectional side elevation of a portion of the punching device, showing magnets.

Fig. 10 is a diagram of the electric circuits.

Fig. 11 is a detail elevation of the escape- 70 ment mechanism of the punching device, and

Fig. 12 is a detail plan view of the escape- 75 mechanism.

Cash register

In the cash register which I have used for purposes of illustration, whenever the outer end of a key lever 20 is depressed the inner end of the lever rises, carrying with it the segment cam 21, each segment cam being of a 80 different length, so that when, on its upward journey, it engages stud 22 on arm 23 of its corresponding differential segment 24, the differential segment will be rotated about its pivot 25 through an arc proportional to the marked 85 value of the key lever 20 which actuated it. At the same time the proper target indicator 26 is raised by its stem 27, to show which key has been depressed. The key coupler 28, pivoted at 29 and resting on top of the rear end 90 of lever 20 is adapted to raise, and then lower, revolution rack 30 (Fig. 7). This occurs during each operation of the register. Rack 30 on one side during its up stroke, and on the other side during its down stroke, meshes with 95 pinion 31 on revolution shaft 32. This results in shaft 32 making a complete revolution during each register operation.

A frequent cash register operation is to partly depress a key in either the cents, dimes, 100

or dollars section of the machine, or in any two of them, and then complete the depression of all the desired keys by fully depressing a key in the other section of the key board.

5 This is accomplished by the action of the key coupler 28 which carries an outwardly-spring-pressed blade 33 which engages notch 34 in the rear end of lever 20 whenever a key is partly depressed, and insures that key completing its stroke whenever the full operation of any other key fully raises the key coupler 28. Key coupler 28 is continuous past all sections of the register, but there are three blades 33, one for each key section corresponding to cents, dimes, and dollars.

10 There is a differential segment 24 (Figs. 6 and 10) for dollars, one for dimes, and one for cents, and each turns a counter wheel 35 by means of pinion 36 which meshes with the

15 differential segment.

16 I have illustrated a common type of cash register and have described only those parts essential to an understanding of my invention, and inasmuch as this type of machine is 20 well known I shall not explain the regular construction further but shall now describe the parts I have added to carry out the purposes of my present invention.

30 Contact mechanism

Pivotedly attached at 37 (Figs. 2 and 6) to each differential segment 24 is an upstanding link 38 having a vertical slot 39 in its upper end and having a shoulder 40 on its rearward edge. Pivoted on shaft 41 is the sector 42, having its circumferential edge serrated as at 43, and having an arm 44 extending upwardly towards the front of the machine. Pin 45, fast in sector 42, passes through slot 40 39 in bar 38, and the spring 46 draws pin 45 always towards the bottom of said slot.

45 The outer end of each arm 44 carries a bifurcated contact piece 47, one finger of which is in contact with arcuate metallic strip 48, and the other finger passes successively into contact with the individual contact blocks 49 whenever arm 44 is moved. Strip 48 and blocks 49 are held in position by insulating block 50, which is in turn secured 50 to the frame of the machine by plates 51 on rods 52 (Figs. 1 and 6). I have illustrated only three arms 44 and corresponding contact sets, one for cents, one for dimes, and one for dollars.

55 When arm 23 of differential segment 24 is raised, it pushes up bar 38, which, in turn, rotates sector 42 and causes contact fingers 47 to traverse contact blocks 48 and 49. Each block 49 corresponds to a digit on counter 60 wheel 35, and the actuating parts are so proportioned that when a certain digit is indicated on the counter wheel, contact piece 47 is in contact with the corresponding block 49, as well as being in contact with strip 48. During the restoring portion of the operating

cycle of the cash register, sector 42 is held in raised position by dog 55 until the end of the restoring operation, at which time dog 55 is knocked out by shoulder 40 on bar 38 whereupon spring 46 draws sector 42 to home position.

65 On the end of shaft 32 (Figs. 7, 8, and 10) is secured a commutator 56 which makes one revolution during each operation of the cash register. Imbedded in the commutator is 70 contact block 57 for the common line, block 58 for dollars, block 59 for dimes, and 60 for cents. Bearing on the commutator and arranged to contact with the above contacts when the commutator rotates, are the brushes 61, 62, 63, and 64 (Figs. 8 and 10).

75 Action of these parts will be further referred to after the punching mechanism has been explained.

80 Punching mechanism

85 The punching mechanism is of a type well known in the art, in which a stack 70 (Fig. 4) of cards to be punched is placed in magazine 71. As a preliminary to operating the punch the operator draws out the rod 72 which carries one card from the bottom of stack 70, forward into the punching section of the machine. Thereafter, when the keys are manipulated by the operator the card is advanced forward one column at a time by the usual escapement mechanism, the escapement operating at each punching operation. These parts are old and well known in punching devices of this kind. After the card is punched 90 the operator withdraws the card at the left end of the machine, reoperates pull rod 72, and punches the next card.

95 In the embodiment I have shown in my drawings I provide 12 punches 75, placed in a row across the device, each punch corresponding to a particular index position on the card. Corresponding to each digit punch is a selecting magnet 76. These magnets, when one is energized, effect the selection of the 100 punches in the following manner. Referring to Fig. 9, a selecting magnet 76, when energized, attracts its armature 77 thus depressing plunger 78, which acts through bell crank 79 to thrust forward an interposer bar 80 to a position above its corresponding punch 75. The forward movement of any interposer bar rocks a bail 81 which pulls link 82 forward and closes contact 83. This establishes a circuit to the main punching magnet 84, which, through arm 85, rocks bail 86 downwardly. Bail 86 is directly over the row of punches 75 and when rocked downwardly depresses any interposer bar or bars which have been moved forward by their selector magnets, and thereby force the corresponding punch or punches through the card. Punches whose interposer bars have not been thrust forward will not be affected, as they will be in the 110 position shown in Fig. 4, with the clearance

115 120 125 130

notch 88 under the bail. The interposer bar is restored to initial position by a spring 101 (Fig. 9). The depression and return to initial position of an interposer bar is also utilized to operate the escapement mechanism. The card while in punching position is held on the surface of frame 102 by a gripper 103 at the forward end (see Figs. 3 and 4) and an abutment 104 at the rear end (Fig. 5). Both the gripper 103 and abutment 104 are rigid with the escapement bar 105 (Figs. 3, 5, 11 and 12). Thus, movement of the escapement bar will through gripper 103 and abutment 104 advance the card. The escapement bar is provided on its lower edge with rack teeth 106 which mesh with a pinion 107, of an ordinary spring motor 108 (Fig. 5). When rod 72 is pulled out to bring a card from the magazine 71 into the punching section, rack teeth 109 at the right end of the rod (see Figs. 4 and 5) rotate pinion 110 on a shaft 111 which carries a pinion 112 meshing with teeth on the bottom of a rod 113 rigidly carried at the rear end of the escapement bar (see Fig. 5). Rotation of pinion 110 results in movement of the escapement bar towards the right (as viewed in Fig. 5). Through teeth 106 on the escapement bar and pinion 107, the spring drum 108 is thereby tensioned. The movement of the escapement bar to the right is permitted by escapement pawls 115 and 116 (see Figs. 5, 11 and 12). Escapement pawl 115 is loosely pivoted on pin 117 of a stationary member 118 while pawl 116 is directly pivoted on frame 119. Pawl 115 has a slot 120 in which is loosely seated a pin 121 of a member 122 (Figs. 5 and 12). Pawl 116 has a notch at the free end in which is a pin 123 on a member 124. Member 122 is freely rotatable on shaft 125 which also freely carries a bail 126 provided with a screw 127 bearing on an extension 128 of member 122. Member 122 in turn has a screw 129 which bears on an extension 130 fixed to member 124, the screw 129 and extension 130 being held in contact by spring 131. Thus when bail 126 rocks to the left as viewed in Figs. 4, 5 and 12, it depresses extension 128 moving pin 121 on member 122 upwardly while the latter through screw 129 moves member 124 and pin 123 thereof downwardly. Referring to Fig. 11, it is seen that upon movement of pin 121 upwardly, pawl 115 will be lifted out of engagement with the escapement teeth on rack 105 while downward movement of pin 123 moves pawl 116 downwardly into contact with the escapement teeth before the escapement rack is released by pawl 115. Bail 126 extends beneath all the interposer bars. Thus when one of the latter is depressed during a punching operation, the bail 126 is moved downward as may be understood from Fig. 4. The completion of the downward movement of bail 126 finds pawl 115 released from the escapement rack. A spring 132 between the member 124 and the pawl 115 (Figs. 11 and 12) moves the pawl 115 forwardly after it has been raised, this movement being permitted due to the play between pin 121 and slot 120 of the pawl 115 and the loose pivoting of the latter. The pawl 115 is thereby positioned on top of the next tooth of the escapement rack.

When the depressed interposer bar is restored to initial position, bail 126 rocks upwardly and member 122 follows. The pin 123 is raised due to this action before the pin 121 is depressed. When pin 123 is raised, pawl 116 is released from the escapement rack and the latter is advanced one tooth space from its previous position by spring motor 108 acting through pinion 107 after which the pawl 115 drops into the next tooth notch and holds the escapement against further movement. The card is thereby advanced one column each time a punching operation is effected. The movement of bail 86 is also utilized to open contact 89 (Figs. 5 and 10), actuation being effected by bracket 90 fixed to bail 86. The purpose of contact 89 will be explained later. 91 is a pull rod contact which cuts out the punch-selecting magnets while pull rod 72 is being operated, in order to prevent punching operations during that time. Switch 92 may be used to break the punching circuit when it is desired to operate the cash register without punching.

Operation

Whenever the keys 20 of the cash register are depressed to record a transaction, the arms 44 are moved as described above, and their contact members 47 are positioned differentially on their respective contact blocks. For instance, if the amount of the transaction is \$3.51 the three contact members will be positioned as shown in Fig. 10, in which the upper contact segment represents dollars, the middle segment dimes, and the lowest segment cents. Each block 49 represents a digit and each is wired to a corresponding magnet 76. On the down stroke of a key 20 the contacts are positioned but no impulse is sent through the magnets. On the return stroke of the key, commutator 56 sends impulses successively through the dollar, dimes, and cents circuits, and punches holes successively in the dollar, dimes, and cents columns of the record card, which has been placed by the operator in proper position in the punching device.

The scheme of operation can readily be understood by referring to circuit diagram, Fig. 10, in which current is admitted to the line by switch 93. When commutator 56 is rotated, in the direction indicated by the arrow, and brushes 61 and 62 come simultaneously into contact with blocks 57 and 58, current flows through line 94, contact 89,

line 95, brushes 61 and 62, line 96, upper contact sector 48, contact member 47, block 49, through its corresponding magnet 76, switch 92, contact 91, and back to the source. At 5 the same time part of the current flows through line 97, magnet 84, contact 83 (which, has been closed by the interposer actuated by appropriate magnet 76), and back to the source by line 98. When magnet 84 is energized armature 99 is actuated and the punch 70 is driven through the card by bail 86 (Fig. 9) as previously described. At the same time bracket 90 breaks contact 89 and current through magnet 76 is interrupted and the interposer bar is permitted to be restored by spring 101.

After the first (dollars) punching operation is completed as described above, commutator 20 56, continuing to rotate, brings contact blocks 57 and 59 into contact with brushes 61 and 63 and a circuit is established through line 100 whereupon the proper punch is actuated in the dimes column of the record card, which, during the interval between commutator contacts 58 and 59, has been moved one 25 column further along. After the dimes operation has been performed and the parts restored to normal position, brushes 61 and 64 are connected by blocks 57 and 60 and the 30 digit set up on the cents sector is punched in the cents column of the card, and the recording of that particular cash register operation has been completed, whereupon, as bar 35 moves further downward, shoulder 40 (Fig. 6) trips pawl 55 and sector 42 returns to home position carrying contact member 47 with it. The cash register and punch are then ready for the next transaction.

40 The particular cash register utilized in connection with the present invention of the so-called press down key type. It is well known that with registers of this character that the power available for operating the register is not great. If excessive load is required in operating the register it has been found that the operator cannot apply this power through his or her fingers. Consequently, the registering operating mechanism and appurtenant parts must be made to operate with a minimum power. According to 45 the present invention the punching apparatus or unit is separate from the register. No additional power is required to operate the punches inasmuch as the punching operation itself is performed by means of the electric solenoid device of the punching attachment. The operator of the cash register operates it in the usual manner. The only additional power which is required is that necessary for setting up the contact devices. After the contact devices have been set up these control circuits select the proper punches for operation. Thereafter the punching operation proper is initiated and this punching operation which requires considerable power

is brought about by the action of the independent motive power device of the punching attachment.

It will be understood that the punching attachment herein disclosed can be readily 70 associated with cash registers which are now in use by providing the supplementary controlling contact elements upon the differential segments.

The construction disclosed in the present 75 invention provides means whereby upon the depression of a single key representative of a multidenominational amount there may be a successive punch control successively selecting the punches for operation and for 80 initiating a punching operation after each selection has been made for a particular denominational order.

I claim:

1. In combination with a cash register and 85 a separable punching mechanism having provisions for punching a tabulating card successively in one column after another, means in said cash register brought into operation by a single registering operation 90 thereof for effecting a selection of a plurality of punches which are successively brought into operation in said punching attachment.

2. In combination with a cash register and 95 a separate punching mechanism having provisions for punching a tabulating card successively in one column after another, selecting means in said cash register brought into operation by a single registering operation 100 thereof for controlling a plurality of successive punching operations of said punching mechanism.

3. In a combined punch and register 105 wherein the latter includes differential actuators for entering items, said actuators being manually operated in entering an item and automatically restored after an item entering operation, means controlled in accordance with the operation of said actuators during their manual actuation for selecting 110 the punches adapted to record the entered items in the form of perforations on a record sheet, and means controlled during automatic restoration of the actuators for operating the punches selected by said first-named means.

4. In combination with an adding machine, a punch-press having a plurality of punches, a solenoid cooperating with each punch, switches respectively cooperating one 115 with each of a plurality of the adding machine keys in a manner adapted to be closed when a key is depressed, connections respectively between the corresponding solenoids and key switches, means for operating the adding machine, and a switch in the said connections adapted to be closed by the operating 120 of the last named means in a manner completing such connections where the key switches are closed and depressing the cor- 125
